UNITED STATES PATENT OFFICE.

WILBERT B. McCOY, OF CLEVELAND, OHIO.

DESIGN FOR A BATH HOOD.

Application filed August 7, 1922. Serial No. 3,304. Term of patent 3½ years.

To all whom it may concern:

Be it known that I, WILBERT B. McCoy, a citizen of the United States, residing at Cleveland, in the county of Cuyahoga and State of Ohio, have invented a new, original, and ornamental Design for a Bath Hood, of which the following is a specification, reference being had to the accompanying drawing, forming part hereof, which is a side view of a bath hood, exhibiting my new design.

I claim:

The ornamental design for a bath hood, as shown.

WILBERT B. McCOY.
